[57] CLAIM

The ornamental design for a tempered loop fret, as shown and described.

DESCRIPTION

FIG. 1 is a perspective view of a tempered loop fret, showing my new design thereof;

FIG. 2 is a left-side elevational view thereof, and the right side-elevational view is a mirror image thereof and is not shown;

FIG. 3 is a top plan view thereof;

FIG. 4 is a bottom plan view thereof;

FIG. 5 is a top plan view of the loop portion of the present invention showing an alternative embodiment thereof; and, FIG. 6 is a top plan view of the loop portion of the present invention showing another alternative embodiment thereof. The undisclosed portions of the fret in FIG. 5 and FIG. 6 are identical to that shown in FIGS. 1-4.
